PROCESS FOR THE SEPARATION OF SEEDS
BY FROTH FLOTATION

Theodore Earle, Pacific Palisades, Calif.

No Drawing. Application October 15, 1936,
Serial No. 105,632

17 Claims. (Cl. 209—163)

This invention relates to a process or method for the separation and classification of seeds, and more particularly to a process or method for the application of froth flotation for the successful separation and classification of plant and grass seeds, and has as an object to provide an improved process whereby mixed seeds of different kinds may be separated and classified according to their respective natures, and whereby seeds of a given variety may be separated and classified according to their relative fertility and potential strength.

A further object of the invention is to provide an improved process susceptible of ready, convenient and inexpensive practice to separate and classify plant seeds according to the variety of seed or according to the relative fertility and strength of seeds in a given variety, or both.

A further object of the invention is to provide an improved process whereby the principles of froth flotation may be practically and successfully applied to the separation and classification of plant seeds, either for isolation of a given variety of seed from a mixture of different varieties or for the selection of the relatively stronger and more fertile seeds within a given variety.

It has long been recognized that the various minerals and combinations of minerals present distinct characteristics which may be utilized to effect their separation through the process which has come to be known as froth flotation. I have found that different varieties of plant and grass seeds, and seeds of different fertility within a given variety of seed, have different and definite adsorptive and other characteristics, rendering the principle of froth flotation available for their practical classification and selective separation. However, in carrying out such process certain problems are met which do not arise in minerals separation. Thus certain features must be borne in mind and the reagent to be employed must be selected accordingly, e. g., as to whether the seed is to be used as a food, the effect of the reagent on the sprouting or growing qualities on the seed, whether the seed is to be immediately planted, the presence or absence of the natural husk or hull covering the seed, the character of the soil or climate obtaining during the growth of the seed insofar as the same may affect the characteristics thereof in the application of the process, and the bulk, mass and density of the seed under treatment and the strength of the froth bubbles necessary to effect separation thereof.

Froth flotation as used in the improved proc-

ess and as referred to herein is that conventional and well-understood method which involves repeated and continued agitation of the material to be separated or classified within and through a body of liquid to which suitable reagents have been introduced in one manner or another for the production of a froth bed which forms on and is supported above the liquid body. There are several standard types of froth flotation apparatus which may be employed in the adaptation of froth flotation to the separation and classification of plant seeds, but it is to be noted that the froth flotation employed in the improved process differs materially from "float and sink" methods and from separatory methods utilizing surface tension of a liquid, in that the froth flotation technique includes continued agitation of the liquid body and recirculation of the material under treatment through said liquid body to elimination of the concentrates from the liquid body and into the froth bed wherewith said concentrates are removed from the flotation apparatus.

For the treatment of certain of the smaller seeds a froth flotation machine of standard impeller type will prove reasonably satisfactory, but the larger seeds are subject to damage thereby; thus, in general, the flotation machine designed for agitation by means of compressed air or gas is therefore preferred. The latter type of machine may be modified by the addition of a specially designed impeller, designed to minimize the possibility of damage to the seed, in which case the impeller acts to diffuse and spread the air or gas stream throughout the liquid body.

In determining the principles involved, a great deal of experimental work was done, with many types and varieties of plant seed, and in every instance some degree of effective separation was obtained, such separations being followed by planting under identical conditions and comparison of growing capacities. It was found that in some cases the more fertile seed will separate out as a froth concentrate, but in other cases the reverse is true. While there is an obvious difference in those portions of a given variety of seed separated by the improved method it cannot be said that the better seeds will always appear as concentrates in the flotation cell, since for each variety of seed separation germination and rate of growth tests must be completed to determine the relative strength of the tails and concentrates resulting when that particular seed is treated with given reagents, but it is certain that the selective separation attained is positive.

and efficient. In some cases it may be desirable to condition the seed with certain reagents prior to its treatment in the froth flotation machine and in other instances same may be unnecessary; 5 the desirability of such conditioning is readily determinable by test in the case of any given variety or combination.

In a practical application of the improved process, the first step may involve proper preliminary treatment in cases where desirable. 10 In certain cases, a thorough water-wetting of all of the seed surfaces is necessary to modify and adapt the surface characteristics of the seed for the desired reaction with the reagent before its 15 addition to and agitation with the seed. In any event, it is highly important that the seed to be separated should be completely immersed in water at some time during the flotation treatment.

20 The next or coincident phase of the improved process comprises agitation of the seed in a froth flotation machine in the presence of suitable reagents. For this phase of the process the seeds to be separated may be divided into four general 25 classes: (1) Seeds with hard shells or hulls enclosing the kernels, viz., alfalfa, clover, turnip; (2) Seeds with husks on the kernels, viz., oats, blue grass; (3) Seeds without hulls, shells, or husks, viz., threshed seeds; (4) Seeds representing 30 various combinations of (1), (2) and (3). Each of the above classes may be further divided into sub-classes and grouped according to seed 35 surface characteristics, such as lustrous, smooth, rough, dull, etc., each of which characteristics is productive of a definite flotation effect with a given reagent.

The difference in the surface characteristics of the seeds will require variation and specific adaptation of the reagents employed and the method 40 utilized in feeding the seeds to the flotation machine. In general, seeds in classes (1) and (2) exhibit a preference for frothing reagents, while those in class (3) react floatatively with certain of the fatty acids and their derivatives; but similar 45 seed varieties in either class (1), (2) or (3) may well exhibit differing preferences for reagents or may react differently in point of time to the same reagent. Frothing reagents, including pine oil, 50 terpineol, cresylic acid, the lower and high alcohols, tar oil, "Airflot", and in general any reagents which are capable of sufficiently lowering 55 the surface tension of the water, when added in small amounts, were employed, alone and in various combinations with vegetable oils and highly refined mineral oils; oleic acid and other fatty acids and their derivatives were employed for collecting purposes. Certain seeds carry enough 60 natural frother to eliminate addition of a froth reagent. The amount of reagent required will vary between a top limit of forty pounds of any one reagent per ton of seed and a lower limit amounting to only a fraction of one per cent by weight of seed.

Better results may be had in some instances 65 by feeding the seed into the machine and into the liquid below the froth bed and in other instances by feeding the seed through the froth bed and thence into the liquid. This arises from the fact that where frothers or other relatively insoluble 70 or slightly water soluble reagents are employed, such reagents tend to concentrate on the liquid surface immediately below the froth bed; in such case, seed introduced below the froth line will require longer agitation, and the softening effect 75 of the liquid on the seed covering may vary the

normal floatative characteristic. For example: If alfalfa seed be introduced through a froth formed by a reagent of the type of Du Pont frother "B23" all of the pure and fertile seed will come up into the froth bed, while if the same seed be introduced below the froth level, only twenty-five to fifty percent of the pure and fertile seed will float. On the contrary, when Indica clover is fed through a froth of the type above noted, 10 none of the clover will float. Even when the seed is fed through the froth bed, thorough agitation of the machine contents must be had to bring all of the seed material into and through the liquid so that all of the seed material shall be at some time completely immersed in the liquid charge. 15 Only by thorough agitation and recirculation of the seed material through the liquid charge of the machine can a clean separation be had. Undue retention of the seed in the liquid charge is apt to change characteristics of the seed, and in 20 general the more quickly the separation is made the better is the result, there being a thorough immersion for a brief period. However, in some cases a longer immersion than is generally employed may be desirable. An example of this is 25 a mixture of wild morning glory seed (*Convolvulus arvensis*) and Sudan grass seed, which latter does not lose its smooth glossy appearance after prolonged immersion. In such separation the grass seed comes away as a froth concentrate 30 while the morning glory seed remains as tails.

Generally, reagents such as the lower alcohols do not function as well, alone, as do those that are more persistent in respect to evaporation, such as pine oil, terpineol, and the like. To 35 strengthen certain bubble walls and give them a protective armor, such substances as finely ground sulphur, lime-stone, lime, and the like, may be added in small amounts, the addition of such substances frequently being of additional 40 benefit in destroying fungus growth and similar infection carried by the seeds.

As in the floatative separation of minerals, the pH value of the water in the flotation machine is a factor which must be given consideration and 45 regulation in the manner and for the purpose now well understood in the art of froth flotation. In fact, any of the controlling factors entering into minerals separation by froth flotation may be of corresponding value and use in the froth flotation 50 separation of seeds.

The final phase of the improved process involves separate removal of the concentrates, middlings, and tails from the froth flotation machine and ultimate recovery of the seed comprising 55 such separate portions. The froth carrying the concentrates may be caused to overflow away from the flotation machine, as is common practice in minerals separation, or the froth bed may be skimmed, lifted, or otherwise separated with its 60 seed burden from the liquid charge within the flotation machine.

In some instances it is possible to effect a separation between seeds of different varieties and simultaneously obtain a selective separation as to 65 relative seed strength of one of the varieties through application of the improved process. As an example, a mixture of blue grass seed and devil grass seed was treated by the improved process using pine oil and the Du Pont frothers 70 "B-23" and "B-24" as alternative reagents. In the presence of the reagents noted, the dead and unfertile seeds of blue grass and the live seeds of devil grass collect as concentrates in the froth while the fertile blue grass seeds are left as tails 75

in the machine, so that with a single frothing reagent a simultaneous separation of the mixture can be made with recovery of the fertile blue grass seeds freed from the unfertile and undesirable seed admixed therewith.

Typical examples of separations obtained through practice of the improved process are submitted herebelow. In the first six tests shown, the same procedure was followed throughout.

10 The seed to be separated was first slowly stirred and agitated in water, either in the flotation machine or in a separate vessel, until all of the grain surfaces were thoroughly wet. The wet seed was subsequently conditioned with the reagents employed and the liquid level in the froth flotation machine then brought to a height which would provide a froth bed of an inch or more in depth and the machine then actuated to provide a circulation and recirculation of the seeds in the presence of the suitable reagents. Only those seeds that actually came up into the froth were removed as concentrates and the balance were considered tails. After separation was completed, the excess water was drained from the separated seed portions through a one hundred mesh screen, additional water removed through use of a suction filter, and the seed then finally dried over a low heat. The separated portions were then weighed for total and relative weights, a certain number of seeds or a certain volume from each seed portion was then planted together with a corresponding number or volume of the unseparated seed, and a careful comparative check was made.

35 1—Lettuce seed—100 grams of the seed was first stirred in water for two minutes, one pound of terpineol per ton of seed then added and the mixture conditioned for one minute. The separation resulted in 85 grams of concentrates and 15 grams of tails. 100 seeds from both concentrates and tails were then planted and the following growth observed: In four days: concentrates, 61 sprouts; tails, 7 sprouts. In eighteen days: concentrates, 86 sprouts, all strong plants; tails, 9 sprouts, two strong plants.

2—White Clover—100 grams of the seed was thoroughly wetted by stirring in water for two minutes and then was added, per ton of seed, one pound of oleic acid, two pounds of pine oil, and one pound of Du Pont frother "B-23", the said reagents and seed being conditioned for two minutes. After separation was completed 53.2 grams of tails were recovered, 25 cc. of the concentrates weighing 19.6 grams as against a weight of 19.2 grams for a corresponding amount of tails. The concentrates were light colored seeds while the tails were dark in color. 100 seeds from the crude material, the concentrates and tails were then planted with the following results: In four days: crude, 25 sprouts; concentrates, 39 sprouts; tails, 9 sprouts. In eight days: crude, 70 sprouts, concentrates, 96 sprouts, tails 74 sprouts. In thirteen days: crude, 71 sprouts (51 over $\frac{1}{2}$ "), concentrates, 100 sprouts (76 over $\frac{3}{4}$ "), tails, 75 sprouts (66 over $\frac{1}{2}$ "). The leaves of the concentrate seedlings were much finer than those of the tails seedlings.

3—Blue grass—100 grams of the seed was stirred in water for five minutes and then conditioned for two minutes with Du Pont frother "B-24" in the amount of two pounds per ton of seed. The separation produced 36.3 grams of concentrates of which 25 cc. weighed 5.7 grams and 63.4 grams of tails of which 25 cc. weighed 7.8 grams,

the concentrates being much lighter in color than the tails.

5 cc. each of concentrates, tails and crude seed was planted in a flat. The growth of the concentrate was only about 5% as good as the growth of the tails at the end of twelve days. The crude seed grew better for the first five days but at the end of twelve days the tails were 50% stronger than the crude.

10 100 seeds each of concentrates, tails and crude were planted on blotting paper with the following results: In five days: crude, 9 sprouts; concentrates, 1 sprout; tails, 12 sprouts. In twelve days: crude, 76 sprouts; concentrates, 4 sprouts; tails, 94 sprouts.

4—Alfalfa—100 grams of seed was stirred in water for two minutes and then conditioned for two minutes with two pounds per ton of seed of Du Pont frother "B-23" and one pound per ton of seed of oleic acid. The separation resulted in 57.2 grams of concentrates of which 25 cc. weighed 18.3 grams and 42.8 grams of tails of which 25 cc. weighed 18.3 grams, the concentrates being much lighter in color than the tails.

25 100 seeds each from the concentrates and tails were planted with the following results: In two days: concentrates, 55 sprouts; tails, 72 sprouts. In eight days: concentrates, 96 sprouts (90 sprouts over $\frac{1}{2}$ "); tails, 90 sprouts (85 sprouts over $\frac{1}{2}$ ").

30 5—Sugar beets—100 grams of the seed was stirred in water for two minutes and then conditioned for two minutes with two pounds per ton of seed of Du Pont frother "B-23". The separation resulted in 88.7 grams of concentrates of which 25 cc. weighed 6.0 grams and 11.3 grams of tails of which 25 cc. weighed 7.2 grams. The seeds in the tails were all small while the concentrates carried both large and small seeds.

35 42 seeds each from the concentrates and tails were planted with the following results: In three days: concentrates, 3 sprouts; tails, 1 sprout. In nine days: concentrates, 42 sprouts (all over 3" high); tails, 41 sprouts (23 are 2" high). With the exception of seven, all of the sprouts from the tails were poor, weak plants with weak stems.

40 6—Oats—100 grams of the seed was stirred in water for two minutes and then conditioned for one minute with 1.5 pounds Du Pont frother and one pound terpineol per ton of seed. All of the seed with the exception of 19 oat seeds and the weed seeds floated, there being no weed seeds in the concentrates. The concentrates and tails were planted on blotting paper and from 100 seeds of the concentrates 99 sprouts appeared in six days. On the oat seeds in the tails only few sprouted and produced good plants, the remaining seeds drying out with no evidence of germination.

45 Indicative of the variation in separation obtainable through variation in the method of feeding the seed material to the flotation machine, the following example of a comparative test is presented:

50 A flotation machine was charged with water to which one drop of Du Pont frother "B-23" was added and the mixture was then agitated with air until a froth one-fourth of an inch thick was formed. 100 grams of a mixture of alfalfa and Dodder, (*Cuscuta*) seeds was then fed to the machine through the froth bed and agitated in the machine. 90.6 grams of the seeds floated as a concentrate and the tails weighed 9.4 grams. Crude, 5 grams; by count there were eleven Dodder seeds. Concentrates, 5 grams; by count there was one Dodder seed. Tails, 5 grams; by

count there were 51 Dodder seeds. The above shows that the tails comprising less than ten percent of the mixture carried eighty-five percent of the Dodder seed.

5. Using 100 grams of the same seed mixture last above noted and the same amount and kind of reagents, but varying the technique by first water-wetting the seed prior to addition of the frothing reagent, 38 grams only of alfalfa seed was floated and recovered as a froth concentrate.

10 Since it is necessary to change and modify the specific technique of any given application of the improved process in adapting the process for use on and with seeds of differing varieties, I 15 wish to be understood as being limited solely by the scope of the appended claims rather than by any specific details and recitation of the foregoing description.

I claim as my invention—

20 1. A process for the classification and selective separation of plant seeds which comprises immersion of the seeds in water, addition of a flotation frothing reagent, addition to the mixture of seed and reagent of pulverized insoluble minerals

25 as a strengthening armor for froth bubbles, and subsequent agitation of the resultant admixture in froth-held flotation apparatus for the separation of the seed material into froth concentrates and non-floating tails.

30 2. The method of utilizing natural differences in the surface characteristics of seeds to separate relatively more fertile seeds in a given variety from relatively less fertile seeds of the same variety, which consists of subjecting the seed to violent agitation in froth flotation apparatus in the presence of a reagent consisting of a relatively minute amount of a true frother, for elevation of the seed having one relative fertility characteristic as a concentrate held in the froth bed and separation therefrom of the seed having the other relative fertility characteristic as a tailings product.

35 3. The method of utilizing natural differences in the surface characteristics of seeds to separate the relatively more fertile seed of a given variety from the relatively less fertile seed of said variety and from a second variety of seed intermixed therewith, which consists of first subjecting the intermixed seed to violent agitation in 40 froth flotation apparatus in the presence of a reagent consisting of a relatively minute amount of a true frother, for elevation of one seed variety as a concentrate held in the froth bed and separation therefrom of the other variety as a tailings product, recovering the desired seed variety, and subsequently subjecting the recovered seed to violent agitation in froth flotation apparatus in the presence of a reagent consisting of a relatively minute amount of a true frother, for elevation of the seed having one relative fertility characteristic as a concentrate held in the froth bed and separation therefrom of the seed having the other relative fertility characteristic as a tailings product.

45 4. The method of utilizing natural differences in the surface characteristics of seeds to separate one variety of seed from a second variety intermixed therewith, which consists of feeding the intermixed seed to froth flotation apparatus 50 through a froth bed formed in said apparatus by the use of a reagent consisting of a relatively minute amount of a true frother, and subjecting said seed to violent agitation in the apparatus in the presence of said reagent for elevation of one seed variety as a concentrate held in the froth bed

and separation therefrom of the other variety as a tailings product.

5. The method of utilizing natural differences in the surface characteristics of seeds to separate one variety of seed from a second variety intermixed therewith, which consists of feeding the intermixed seed to froth flotation apparatus through a froth bed formed in said apparatus through the use of a reagent consisting of a relatively minute amount of a true frother and subjecting said seed to violent agitation in said apparatus in the presence of said reagent and a relatively minute amount of a collecting reagent, for elevation of one seed variety as a concentrate held in the froth bed and separation therefrom of the other variety as a tailings product.

10 6. The method of utilizing natural differences in the surface characteristics of seeds to separate relatively more fertile seed of a given variety from relatively less fertile seed of said variety, 15 which consists of feeding the seed to froth flotation apparatus through a forth bed formed in said apparatus by the use of a reagent consisting of a relatively minute amount of a true frother, and subjecting said seed to violent agitation in 20 said apparatus, for elevation of the seed having one relative fertility characteristic as a concentrate held in the froth bed and separation therefrom of the seed having the other relative fertility characteristic as a tailings product.

25 7. The method of utilizing natural differences in the surface characteristics of seeds to separate relatively more fertile seed of a given variety from relatively less fertile seed of said variety, which consists of feeding the seed to froth flotation apparatus through a froth bed formed in said apparatus by the use of a reagent consisting of a relatively minute amount of a true frother, and subjecting said seed to violent agitation in 30 said apparatus in the presence of said reagent and a relatively minute amount of a collecting reagent, for elevation of the seed having one relative fertility characteristic as a concentrate held in the froth bed and separation therefrom of the seed having the other relative fertility characteristic as a tailings product.

35 8. The method of utilizing natural differences in the surface characteristics of seeds to separate relatively more fertile seed of a given variety from relatively less fertile seed of said variety and from a second variety of seed intermixed therewith, which consists of first subjecting the intermixed seed to violent agitation in froth flotation apparatus in the presence of a reagent consisting of a relatively minute amount of a true frother, for elevation of one seed variety as a concentrate held in the froth bed and separation therefrom of the other variety as a tailings product, recovering the desired seed variety, feeding the recovered seed to froth flotation apparatus through a froth bed formed in said apparatus through the use of a reagent consisting of a relatively minute amount of a true frother, and subjecting said seed to violent agitation in said apparatus in the presence of said reagent, for elevation of the seed having one relative fertility characteristic as a concentrate held in the froth bed and separation therefrom of the seed having the other relative fertility characteristic as a tailings product.

40 9. The method of utilizing natural differences in the surface characteristics of seeds to separate relatively more fertile seed of a given variety from relatively less fertile seed of said variety and from a second variety of seed intermixed

therewith, which consists of first subjecting the intermixed seed to violent agitation in froth flotation apparatus in the presence of a reagent consisting of a relatively minute amount of a true frother, for elevation of one seed variety as a concentrate held in the froth bed and separation therefrom of the other variety as a tailings product, recovering the desired seed variety, feeding the recovered seed to froth flotation apparatus through a froth bed formed in said apparatus through the use of a reagent consisting of a relatively minute amount of a true frother, and subjecting said seed to violent agitation in said apparatus in the presence of said reagent and a relatively minute amount of a collector, for elevation of the seed having one relative fertility characteristic as a concentrate held in the froth bed and separation therefrom of the seed having the other relative fertility characteristic as a tailings product.

10. The method of utilizing natural differences in the surface characteristics of seeds to separate relatively more fertile seed of a given variety from relatively less fertile seed of said variety and from a second seed variety intermixed therewith, which consists of feeding the intermixed seed to froth flotation apparatus through a froth bed formed in said apparatus by the use of a reagent consisting of a relatively minute amount of a true frother, subjecting said seed to violent agitation in said apparatus in the presence of said reagent, for elevation of one seed variety as a concentrate held in the froth bed and separation therefrom of the other variety as a tailings product, recovering the desired seed variety, feeding the recovered seed to froth flotation apparatus through a froth bed formed in said apparatus through the use of a reagent consisting of a relatively minute amount of a true frother, and subjecting said seed to violent agitation in said apparatus in the presence of said reagent, for elevation of the seed having one relative fertility characteristic as a concentrate held in the froth bed and separation therefrom of the seed having the other relative fertility characteristic as a tailings product.

40 11. The method of utilizing natural differences in the surface characteristics of seeds to separate relatively more fertile seed of a given variety from relatively less fertile seed of said variety and from a second seed variety intermixed therewith, which consists of feeding the intermixed seed to froth flotation apparatus through a froth bed formed in said apparatus by the use of a reagent consisting of a relatively minute amount of a true frother, subjecting said seed to violent agitation in said apparatus in the presence of said reagent and a relatively minute amount of a collector, for elevation of one seed variety as a concentrate held in the froth bed and separation therefrom 45 of the other variety as a tailings product, recovering the desired seed variety, feeding the recovered seed to froth flotation apparatus through a froth bed formed in said apparatus through the use of a reagent consisting of a relatively minute amount of a true frother, and subjecting said seed to violent agitation in said apparatus in the presence of said reagent, for elevation of the seed having one relative fertility characteristic as a concentrate held in the froth bed and separation therefrom 50 of the seed having the other relative fertility characteristic as a tailings product.

55 12. The method of utilizing natural differences in the surface characteristics of seed to separate relatively more fertile seed of a given variety from relatively less fertile seed of said variety and

from a second seed variety intermixed therewith, which consists of feeding the intermixed seed to froth flotation apparatus through a froth bed formed in said apparatus by the use of a reagent consisting of a relatively minute amount of a true frother, subjecting said seed to violent agitation in said apparatus in the presence of said reagent and a relatively minute amount of a collector, for elevation of one seed variety as a concentrate held in the froth bed and separation 10 therefrom of the other variety as a tailings product, recovering the desired seed variety, feeding the recovered seed to froth flotation apparatus through a froth bed formed in said apparatus through the use of a reagent consisting of a relatively minute amount of a true frother, and subjecting said seed to violent agitation in said apparatus in the presence of said reagent and a relatively minute amount of a collector, for elevation 15 of the seed having one relative fertility characteristic as a concentrate held in the froth bed and separation therefrom of the seed having the other relative fertility characteristic as a tailings product.

13. The method of utilizing naturally differences in the surface characteristics of seeds to separate relatively more fertile seed of a given variety from relatively less fertile seed of said variety and from a second seed variety intermixed therewith, which consists of feeding the intermixed seed to froth flotation apparatus through a froth bed formed in said apparatus by the use of a reagent consisting of a relatively minute amount of a true frother, subjecting said seed to violent agitation in said apparatus in the presence of said reagent and a relatively minute amount of a collector, for elevation of one seed variety as a concentrate held in the froth bed and separation therefrom of the other variety as a tailings product, recovering the desired seed 40 variety, feeding the recovered seed to froth flotation apparatus through a froth bed formed in said apparatus through the use of a reagent consisting of a relatively minute amount of a true frother, and subjecting said seed to violent agitation in said apparatus in the presence of said reagent and a relatively minute amount of a collector, for elevation of the seed having one relative fertility characteristic as a concentrate held in the froth bed and separation therefrom 45 of the seed having the other relative fertility characteristic as a tailing product.

14. The method of utilizing natural differences in the surface characteristics of seeds to separate the relatively more fertile seed of a first 50 variety from the relatively less fertile seed of said variety and from a second variety of seed intermixed therewith, which consists of subjecting the intermixed seed to violent agitation in froth flotation apparatus in the presence of a reagent consisting of a relatively minute amount of a true frother, for elevation of the seed of said first variety having one relative fertility characteristic as a concentrate held in the froth bed and separation therefrom of the seed of said first 55 variety having the other relative fertility characteristic as a tailings product, and for separation of the seed of said second variety, as a part of one of said products, from the relatively more fertile seed of said first variety.

70 15. The method of utilizing natural differences in the surface characteristics of seeds to separate the relatively more fertile seed of a first variety from the relatively less fertile seed of said variety and from a second variety of seed intermixed 75

- therewith, which consists of subjecting the inter-mixed seed to violent agitation in froth flotation apparatus in the presence of a reagent consisting of a relatively minute amount of a true frother, 5 and in the presence of a relatively minute amount of a collecting reagent, for elevation of the seed of said first variety having one relative fertility characteristic as a concentrate held in the froth bed and separation therefrom of the seed of said 10 first variety having the other relative fertility characteristic as a tailings product, and for separation of the seed of said second variety, as a part of one of said products, from the relatively more fertile seed of said first variety.
- 15 16. The method of utilizing natural differences in the surface characteristics of seeds to separate the relatively more fertile seed of a first variety from the relatively less fertile seed of said variety and from a second variety of seed intermixed 20 therewith, which consists of feeding the inter-mixed seed to froth flotation apparatus through a froth bed formed in said apparatus through the use of a reagent consisting of a relatively minute amount of a true frother and subjecting said seed 25 to violent agitation in said apparatus in the presence of said reagent, for elevation of the seed of said first variety having one relative fertility characteristic as a concentrate held in the froth bed and separation therefrom of the

seed of said first variety having the other relative fertility characteristic as a tailings product, and for separation of the seed of said second variety, as a part of one of said products, from the relatively more fertile seed of said first 5 variety.

17. The method of utilizing natural differences in the surface characteristics of seeds to separate the relatively more fertile seed of a first variety from the relatively less fertile seed of said variety 10 and from a second variety of seed intermixed therewith, which consists of feeding the inter-mixed seed to froth flotation apparatus through a froth bed formed in said apparatus through the use of a reagent consisting of a relatively minute 15 amount of a true frother and subjecting said seed to violent agitation in said apparatus in the presence of said reagent, and in the presence of a relatively minute amount of a collecting reagent, for elevation of the seed of said first 20 variety having one relative fertility characteristic as a concentrate held in the froth bed and separation therefrom off the seed of said first variety having the other relative fertility characteristic as a tailings product, and for separation of the 25 seed of said second variety, as a part of one of said products, from the relatively more fertile seed of said first variety.

THEODORE EARLE.
